UNITED STATES PATENT OFFICE

103,573

DESIGN FOR A PHOTOGRAPHIC CAMERA

Albert S. Howell, Chicago, Ill., assignor to The Bell & Howell Company, Chicago, Ill., a corporation of Illinois

Application January 6, 1936, Serial No. 60,448
In Japan October 9, 1935

Term of patent 14 years

To all whom it may concern:

Be it known that I, Albert S. Howell, a citizen of the United States, residing at Chicago, in the county of Cook and State of Illinois, have invented a new, original, and ornamental Design for a Photographic Camera, of which the following is a specification, reference being had to the accompanying drawings, forming a part thereof.

In the said drawings:—

Figure 1 is a front elevational view of a photographic camera, embodying my new design;

Figure 2 is a side elevational view of the same; Figure 3 is a rear elevational view of the same; and

Figure 4 is a side elevational view taken oppositely with reference to Figure 2.

I claim:

The ornamental design for a photographic camera, as shown.

ALBERT S. HOWELL.
